(57) **CLAIM**

The ornamental design for a storage rack for electric tool as shown and described.

DESCRIPTION

FIG. 1 is a perspective view of a storage rack for electric tool showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is an enlarged top plan view thereof;

FIG. 8 is an enlarged bottom plan view thereof;

FIG. 9 is an enlarged view of portion of FIG. 1; and,

FIG. 10 is an enlarged view of portion of FIG. 1.

The broken lines depict portions of the storage rack for electric tool are for the purpose of illustrating article and form no part of the claimed design. The dot-dash broken lines in the drawings indicates cutoff boundaries for the enlarged detailed portion views and form no part of the claimed design.

1 Claim, 10 Drawing Sheets
